WITNESS: *B. H. Evans*

UNITED STATES PATENT OFFICE

MIGUEL BETANCOURT, OF BRONX, NEW YORK

BIT GAUGE AND POSITIONING OR LEVELING ATTACHMENT

Application filed December 3, 1928. Serial No. 323,550.

This invention relates to improvements in bit guides and levels therefor and has for its primary object, the provision of an attachment for a boring bit by which a user may be guided during the boring of a hole to enable him to bore straight, and which attachment may be adjustably attached to the bit to limit the penetration thereof to permit the accurate boring of a hole or dowel socket of a given depth.

Another object of the invention resides in a bit guide and level which may be used when boring either in a vertical or horizontal plane.

15 A further object of the invention is the provision of a bit guide having interchangeable means by which the same may be applied to bits of various diameters.

20 A still further object is to provide a bit attachment of the above kind which may be compactly carried in the tool chest of a carpenter or mechanic for instant use when desired.

With these and other objects in view, the 25 invention resides in certain novel construction and combination and arrangement of parts, the essential features of which are hereinafter fully described, are particularly pointed out in the appended claims, and 30 are illustrated in the accompanying drawing, in which:—

Figure 1 is a perspective view of my guide and level attachment for use upon a bit.

Figure 2 is a vertical longitudinal sectional view on the line 2—2 of Figure 1.

Figure 3 is a horizontal sectional view on the line 3—3 of Figure 2.

Figure 4 is a side elevation showing the use of my attachment in boring a hole on a horizontal plane.

Figure 5 is a top plan view of the guide and level.

Figure 6 is a perspective view thereof.

Figure 7 is a detail perspective view of one 45 of the interchangeable bore reducer guides.

Referring to the drawings, in which like reference characters refer to like parts throughout the several views thereof, the numeral 10 designates my improved bit guide and level attachment in its entirety which

includes a flat disk or plate 11 having a tubular sleeve 12 extending from one side thereof. The bore 13 of the sleeve extends through the plate and is of a uniform diameter throughout. Mounted in the disk 11 at 55 right angles to each other are two spirit levels 14 which are readable on the outer face of the disk and which are of the usual well-known construction, each of which includes a sealed transparent glass tube 15 filled with liquid to provide an air bubble 16 therein. These spirit levels are sighted by a user when boring a hole on a vertical plane but when the attachment is used for boring on a horizontal plane, the spirit level 17 mounted exteriorly 60 upon the sleeve 12 is sighted. This level 17 is constructed similar to the levels 14 so that a further description is not believed necessary.

Threaded into the wall of the sleeve 12 is 70 a clamping set screw 18 which is screwed tight against the bit 19 as shown in Figure 4 of the drawing when the attachment is applied to a bit of a diameter equal to the inner diameter of the bore 13.

In use, the attachment is clamped to the bit in the manner just described but is adjusted thereon with respect to the free end of the bit for a distance equal to that of the depth of the hole to be bored. This adjustment 80 will enable a dowel socket of a given depth to be accurately drilled, as the end of the sleeve will strike the work when the desired depth is reached and thus limit further cutting. In starting the boring operation, the user places 85 the pointed end of the bit upon the work and axially centers the same by sighting the spirit levels 14 or 17 depending upon whether he is to bore on a vertical or horizontal plane. When the bubble 16 is centered between the 90 ends of the tube or any indicating marks which may be provided thereon, he is assured that the bit is truly centered and proceeds to rotate the bit by the turning of the usual brace in which the bit is held. The operator 95 should watch the spirit levels during the boring operation to guide him and upon any deviation shown by the spirit levels will readily reveal that the bit is not boring in the desired path which may be corrected by 100

the operator again centering the bit. It will therefore be seen that sockets and holes may be formed in a piece of work which are true and of a given depth.

- 5 5. In instances where a bit of a smaller diameter is to be used in connection with my attachment, I provide a set of interchangeable bore reducing elements, one of which is shown at 20 for use in connection with a bit
10 10. 21. The set may be made to accommodate the standard size bits and the same individually used in connection with the guide and level attachment. The bore reducing element 20 includes a tubular sleeve 22 whose
15 15. external diameter is substantially the same as the diameter of the bore 13 so as to snugly fit therein while the internal diameter is the same as the diameter of the bit 21. One end of the sleeve 22 has a plate 23 integral therewith which carries a pin 24 for reception in a hole or socket 25 provided in the disk 11. The sleeve 22 of the reducer is inserted into the bore 13 and is of a length equal to the length thereof while the plate 23 rests flat
20 20. 25 against the disk 11 with the pin 24 in the socket or hole 25. The pin and socket prevent turning of the reducer with respect to the guide and level 10 and align an opening 26 in the sleeve 22 with the set screw 18 to
25 25. 30 allow the set screw to pass therethrough to clamp the attachment to the bit. The reducing element 20 may be readily interchanged by unscrewing the set screw and withdrawing the same from the bore 13.
35 35. While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:—

- 45 45. 1. A bit gauge and positioning or leveling attachment comprising a tubular sleeve, a set screw threaded in said sleeve for clamping the same upon a bit, a disk at one end of said sleeve, and a spirit level mounted in said disk, a bore reducer element fitting into said tubular sleeve and having a bore extending therethrough, said reducer element having a hole therein for the passage of said set screw, and coacting means for preventing accidental turning of said bore reducer member with respect to said sleeve and for aligning said opening with respect to said set screw.
50 50. 2. A bit gauge and positioning and leveling attachment comprising a tubular sleeve having a bore of a uniform diameter throughout, a disk on one end of said tubular sleeve, a set screw threaded into said tubular sleeve by which the same may be clamped to a bit passing therethrough, a reducing sleeve of a diameter to fit within said tubular sleeve and

having a smaller bore therein, said reducing sleeve having an opening therein for the passage of said set screw, a plate on one end of said reducing sleeve for engagement with said disk, and coacting means between said plate and disk for preventing turning of the reducing sleeve with respect to said tubular sleeve and for aligning said opening with said set screw.

70 70. In testimony whereof I have affixed my signature.

MIGUEL BETANCOURT.
